UNITED STATES PATENT OFFICE.

GEORGE WEDDERBURN, OF DUNN LORING, VIRGINIA.

LOCKING MEANS FOR BOTTLES AND THE LIKE.

No. 834,500.

Specification of Letters Patent.

Patented Oct. 30, 1906.

Application filed December 20, 1905. Serial No. 292,574.

To all whom it may concern:

Be it known that I, GEORGE WEDDERBURN, a citizen of the United States, residing at Dunn Loring, in the county of Fairfax and State of Virginia, have invented new and useful Improvements in Locking Means for Bottles and the Like, of which the following is a specification.

This invention relates to locking means for milk-bottles and other analogous receptacles for application to a wall, frame, or other support adjacent to a closure, such as a door.

The primary object of the invention is to provide positively-operating means for holding a filled milk-bottle or the like in positive position close to a door or analogous closure to resist or obstruct nefarious attempts to steal the same and removable only by proper persons from the interior of a dwelling—for instance, by opening the door and releasing the locking means.

A further object of the invention is to provide a locking means for a milk-bottle or analogous device which will resist an attempt to irregularly detach the bottle therefrom when locked either by the insertion of an implement to disengage the locking member or by twisting and pulling the bottle with a view to breaking the locking means or forcing the locking member out of locking engagement.

A still further object of the invention is to provide a locking means for milk-bottles and the like wherein one or more bottles may be held by a single locking member or element.

With these and other objects and advantages in view the invention consists in the construction and arrangement of parts, which will be more fully hereinafter set forth in preferred form.

In the drawings, Figure 1 is a sectional elevation of a portion of a door entrance or closure means, showing the improved locking device and illustrating a milk-bottle as held thereby. Fig. 2 is a horizontal section of the parts as shown by Fig. 1, illustrating the door or closure open and the locking device released. Fig. 3 is a view similar to Fig. 2, showing the door closed and the locking device as being adapted to receive two bottles. Fig. 4 is an enlarged horizontal section of a portion of the keeper or hasp and showing a slight modification of the locking means. Fig. 5 is a view similar to Fig. 4, showing a further modification of the locking member. Similar numerals of reference are employed

to indicate corresponding parts in the several views.

The numeral 1 designates a frame having a base and side wall and may represent the framing of a door or other structure having a closure 2, which in the present instance is shown as a door to illustrate the preferred application of the invention to the entrance of a dwelling, the door or closure 2 controlling the locked and released condition of the improved device.

The improved device comprises a supporting member or strap 3, which is secured at a suitable elevation to the side wall of the frame 1 and has an outer inwardly-curved or arcuate extremity 4, to which a hasp or keeper 5 is movably or pivotally connected. The opposite end of the hasp or keeper 5 is provided with a spring locking-tongue 6 to engage with a locking member 7 of box-like form and movably attached to the inner end of the supporting member 3. This box-like locking member 7 has upper and lower guards 8 and at its free end has an outwardly-extending locking nose or shoulder 9, with which the free end of the spring-tongue 6 is adapted to engage, this tongue 6 when in engagement with the nose or shoulder 9 being inclosed within the locking member 7 and obstructing the introduction into said member of any implement for the purpose of releasing the locking-tongue when the door is closed and has contact with the inner portion of the said member.

The locking member, as shown by Figs. 2, 3, and 4, has a projecting pin 10 for engagement or contact with the door or closure 2 to insure an outward maximum projection of the locking member or a projection to such a degree as to render said member effective as an engaging means for the spring-tongue 6 and thoroughly inclose the latter, as particularly illustrated by Fig. 3.

In Fig. 5 the pin 10 is replaced by an inward swell or protuberance 11, formed as a part of the inner wall of the locking member and indicating that said member may be provided with any form of inward projection for engagement with the door or closure. The keeper or hasp 5 is preferably of semicircular form, and when closed it forms, with the outer curved extremity of the supporting member 3, a circular inclosure which will be of such diameter as to effectively engage the neck of a bottle and prevent removal of the latter by an attempt to draw the rim of the

neck therethrough. In other words, the diameter of the locking device when closed is less than the diameter of the rim of the neck or the head of the bottle.

5 In Fig. 3 a keeper or hasp 12 is shown having two semicircular members and connected to a support 13, provided with correspondingly-curved members 14 and 15, the members 13 and 15 being secured to the side 10 wall of the frame and the hasp or member pivotally connected or hinged to the outer free extremity of the member 15. This modification is intended to indicate that the device may be constructed to hold one or 15 more bottles with equal efficiency.

As an auxiliary retaining means for the bottles or receptacles it is proposed to use at times a lower ring-like keeper 16 of sufficient diameter to embrace the lower portion of the 20 body of the bottle. There will be as many of these ring-like keepers 16 employed as there are seats in the separable locking device above, or one for each bottle held by the main locking device.

25 The spring-tongue 6, as shown by Fig. 5, may form a part of the hasp or keeper, or, as particularly illustrated by Fig. 4, a spring-tongue 17 may be riveted or otherwise secured to the free end of the keeper or hasp; 30 but in either construction the tongue will be of such shape and projection that it will be fully inclosed within the locking member 7 when the keeper or hasp is forced into locking engagement.

35 In preparing the improved locking means for operation the keeper or hasp is thrown out or stands in released position and the door 2 is closed, thus forcing the locking member 7 outwardly, as illustrated in Fig. 3.

40 The milkman in delivering the milk places the neck of the bottle against the supporting member 3 and forces the keeper or hasp 5 around the bottle-neck and into engagement with the locking member 7, the spring-tongue 5

45 carried by the keeper or hasp automatically engaging the locking nose or shoulder at the free end of the said locking member. When the keeper or hasp has thus been arranged, it will be impossible to release the same until

50 the door 2 is opened from the interior of the dwelling. When the door 2 is opened, the resiliency of the spring locking-tongue carried by the keeper or hasp 5 throws the locking member inwardly and renders the separation of the spring-tongue from the locking member very easy and permits a full opening 55 of the keeper or hasp and the removal of the bottle.

The keeper or hasp and the support there- 60 for, as well as the locking member to receive the spring-tongue, can all be cheaply made from suitable sheet metal, and the auxiliary keeper 16 is preferably formed of stiff wire. It will be seen that the supporting members 65 8 and 13 carry all the parts of the locking de-

vice, and when said supporting members are secured in proper position relatively to a door or other movable closure the complete device in the main is applied at a single operation, which is materially advantageous in 70 view of the fact that any one with ordinary judgment is enabled to dispose the device in operative position and without the assistance of skilled labor.

It is proposed to use the locking device for 75 any other purpose where it may be found applicable, and its service is not limited to securing milk-bottles, though this is a preferred adaptation.

The improved locking device will prevent 80 the loss of milk-bottles and the inconvenience often arising to consumers by having such bottles stolen after their delivery.

When the locking device is applied, it forms no material projection or does not interfere with the operation of the closure 2 as a means of closing an entrance.

Other advantages will appear to those using the device, and in view of the simplicity of the several parts the locking means 90 specified may be manufactured and sold at a comparatively small cost.

Having thus fully described the invention, what is claimed as new is—

1. The combination with a closure, of a 95 locking means involving a locking member projectable into locking position by the closure, and a keeper shaped to directly embrace a portion of a milk-bottle and having a resilient locking device to engage the said 100 locking member, the bottle held by the locking means being exposed.

2. The combination with a door, of a locking means involving a locking member projectable into locking position by the closure 105 of the door, and a keeper having seat means to receive and embrace portions of milk-bottles and provided with terminal means for removably engaging the locking member, the bottle held by the locking means being exposed.

3. The combination with a door, of a locking means consisting of a supporting member, a locking member movably connected to the supporting member and projectable into 115 locking position by the closure of the door, and a keeper movably attached to the supporting member and having terminal means to automatically engage the locking member, the keeper being provided with seat means 120 shaped to embrace and directly engage the body portion of a milk-bottle.

4. The combination with a door, of a locking member movably held adjacent to the said door and projectable by the latter into locking position, and a movably-attached keeper having a clasp means to directly embrace a portion of a bottle and terminal means to automatically enter into locking engagement with the locking member, the 130

bottle held by the locking means being exposed.

5. The combination with a door, of locking means involving a locking member having a locking-shoulder and inclosing guards, and a movably - attached keeper having clasp means to directly embrace a portion of a bottle and a terminal device to automatically enter into locking engagement with the said locking member and enter between the guards.

6. The combination with a door, of a locking means involving a movably-mounted locking member having inclosing means, and a movably - attached keeper having seat means to receive and embrace a portion of a milk-bottle and a terminal to engage the locking member, the latter being projected into locking position by the door and releasable only when the door is opened, the bottle held by the locking means being exposed.

7. The combination with a door, of a locking means involving a movably-disposed locking member projectable into locking po-

sition by the closure of the door and releasable from locking position only when the door is opened, the said locking member having a projection to contact with the door, and a movably-attached keeper having seat means to receive and directly embrace a portion of a milk-bottle and a terminal locking device to engage the locking member, the bottle held by the locking means being exposed.

8. The combination with a door, of a locking means involving a movably - mounted locking member, a movably-attached keeper having a terminal to engage the said locking member, the locking member being projected into locking position by the door, and an auxiliary keeper below the said locking means.

In testimony whereof I affix my signature in presence of two witnesses.

GEORGE WEDDERBURN.
